LIGHT EMITTING GAS DISCHARGE MATRIX DISPLAY PANEL

William D. Petty, 524 Clover Lane, Perrysburg, Ohio
43551, and Larry J. Lohmann, 2416 Oak Grove Place,
Toledo, Ohio 43613

Filed Aug. 15, 1972, Ser. No. 280,906

Term of patent 14 years

Int. Cl. D14—02
U.S. Cl. D26—5 C

Fig. 1A

Fig.1B

FIG. 2

FIG. 3

FIG. 4

FIG. 1A is a front elevational view of the left half of a light emitting gas discharge matrix display panel embodying our new design;

FIG. 1B is a front elevational view of the right half thereof;

FIG. 2 is an enlarged fragmentary front elevational view of the upper right corner thereof;

FIG. 3 is an end elevational view thereof; and

FIG. 4 is a bottom plan view thereof with the center broken away for convenience of illustration.

We claim:

The ornamental design for a light emitting gas discharge matrix display panel, as shown and described.
